(57) CLAIM

I claim the ornamental design for a combined silverware stand and brochure, as shown and described.

DESCRIPTION

FIG. 1 is a perspective view of a combined silverware stand and brochure, showing my new design;

FIG. 2 is a front elevational view of FIG. 1;

FIG. 3 is a rear elevational view of FIG. 1;

FIG. 4 is a right-side elevational view of FIG. 1, the left-side elevational view being a mirror image thereof;

FIG. 5 is a top plan view of FIG. 1;

FIG. 6 is a bottom plan view of FIG. 1; and,

FIG. 7 is a bottom plan view thereof, shown in unfolded condition.

The broken lines showing eating utensils in FIG. 1 depict environmental matter and form no part of the claimed design. The broken lines in FIGS. 6 and 7 depict portions of the combined silverware stand and brochure that form no part of the claimed design.
